UNITED STATES PATENT OFFICE.

ADOLPH ROSNER, OF SPRINGFIELD, MASSACHUSETTS, ASSIGNOR TO AMERICAN BOSCH MAGNETO CORPORATION, OF SPRINGFIELD, MASSACHUSETTS, A CORPORATION OF NEW YORK.

LUBRICATOR.

1,390,588.

Specification of Letters Patent. Patented Sept. 13, 1921.

Application filed March 24, 1921. Serial No. 455,144.

To all whom it may concern:

Be it known that I, ADOLPH ROSNER, a citizen of the United States, residing at 4 Ventura street, Springfield, in the county of 5 Hampden, State of Massachusetts, have invented certain new and useful Improvements in Lubricators; and I do hereby declare the following to be a full, clear, and exact description of the invention, such as will 10 enable others skilled in the art to which it appertains to make and use the same.

The present invention relates to oilers for oscillating devices, such as oscillating magnetos, and particularly to one adapted to be 15 carried by the oscillatory mechanism thereof.

In accordance with one part of my invention, the oiler is carried by the trip lever of the oscillating mechanism, so that during 20 operation, oil is caused by the snap action of the trip lever to be actively fed onto the parts to be lubricated, and during rest the oil feed is reduced to a minimum. Preferably the oiler has means, such as laterally 25 extending portions, engaging the trip lever for more rigidly holding it in fixed relation, the lever having, if desired, a squared portion for engagement with such means.

Whether or not the oiler has means for 30 more rigidly holding it in fixed relation to the trip lever, but preferably so, the oiler is, in accordance with another part of my invention secured to the lever by the same means used for securing the lever to the 35 shaft of the oscillatory mechanism thereby simplifying the installation and making it possible to install the oiler on present oscillating mechanism without machining or using special tools or parts.

40 In the preferred embodiment of the invention described hereinafter, the oiler comprises a container having a supporting portion by which the oiler may be rigidly secured to the trip lever by a securing means, 45 the trip lever engaging the means, provided on the supporting portion, having means bearing against and supporting the bottom of the container, thus adding rigidity to the oiler.

50 It is another part of my invention to construct the oiler with a container having a permanently open top and with oil retaining means, and providing the container with means, preferably in the form of upwardly

converging end walls, for retaining the oil 55 retaining means in place so that it will not be cast or shaken loose from the container and also that the oil may be retained and not spilled from the container during its oscillation with the trip lever. The container, 60 whether or not it has means for retaining the oil retaining means in the container, such as, upwardly converging end walls, also has oil dripping means, preferably in the form of 65 depending projections, for receiving oil from the oil retaining means and along which the oil may flow and from which drops of oil 70 may be shaken, during the oscillation of the trip lever and oiler, the drops of oil being cast against the parts to be lubricated. 75 The oil is preferably conducted from the oil retaining means to the exterior of the container, as to the oil dripping means or depending projections, through openings, 75 preferably in the form of slots, provided in the bottom of the oil container adjacent such projections.

As another feature of my invention, I construct or compose my oiler from a single sheet metal blank having portions which 80 when bent and folded, form the bottom, side and end walls of the container together with a supporting portion by which the oiler is secured to the trip lever, the supporting portions having portions which when laterally 85 bent form the portions for engaging the trip lever for maintaining the fixed relation between the trip lever and oiler, so as to generally reinforce and give rigidity to the oiler, dripping portions being also 90 formed integrally with the end wall portions.

In the accompanying drawing illustrating 95 a preferred embodiment of the invention as applied to an oscillating magneto:

Figure 1 is an end view of an oscillating magneto with an oiler in operative position; Fig. 2 is a fragmentary sectional view taken on line 2-2 of Fig. 1; Fig. 3 is a fragmentary sectional view taken on line 3-3 of Fig. 1; Fig. 4 is a longitudinal section of the oiler taken on line 4-4 of Fig. 3; Fig. 5 is a fragmentary sectional view taken on line 5-5 of Fig. 1; Fig. 6 is a perspective view of the oiler; and Fig. 7 is a plan view 100 of the sheet metal blank in developed form from which the oiler is constructed.

Referring more particularly to the draw-

ing the magneto 1 has an end plate 2 carrying laterally extending arms 3 at the ends of which are pivotally mounted rollers 4 carrying an end of oscillating springs 5, the other end of the springs being connected to rollers 6 pivotally mounted upon pins 7 rigidly secured to a yoke portion 8 of a trip lever 9. The trip lever has a tapered socket 10 fitting with the tapered end 11 of the magneto shaft 12, and is maintained in fixed relative position to the shaft 12 by means of a nut 13 threaded upon the screw threaded end 14 of the shaft, a suitable spring lock washer 15 being conveniently interposed between the nut and the trip lever. The trip lever extends downwardly a sufficient distance to be engaged by a roller 16 mounted upon a pin 17 carried as a fixed part of a moving member of an engine, such as the flywheel of the engine. The lower portion 18 of the trip lever has a machined surface 19 against and along which the roller 16 contacts and moves when the trip lever is shifted from the position shown in full lines to that shown in dotted lines in Fig. 1, the roller 16 disengaging the end of the portion 18 in the dotted line position shown.

The oiler is constructed from a single sheet metal blank which may be cut or formed into shape, as by die-pressing or similar modes of manufacture, so as to provide in the sheet side portions 21 and 22, a bottom portion 23, supporting portions 24 and 25, end portions 26 and 27, drip portions 28 and 29, formed integral with the end wall portions, and reinforcing portions 30, 31, 32 and 33, the reinforcing portions, when laterally bent and curved, and adapted to engage with the trip lever as well as with the bottom portion of the oiler, in a manner hereinafter more fully described.

In constructing the oiler the blank may be bent or folded along the dotted lines shown so as to bring the supporting portions 24 and 25 adjacent each other and the side wall portions 21 and 22 in spaced parallel relation with the bottom portion 23 extending from the supporting portion 25 to the side wall portion 22 as is clearly shown in Fig. 3. The end portions are also bent or folded so as to provide depending drip portions 28 and 29 at the ends of the oiler and are maintained in proper relation by bending or folding over the flange portions 34 and 35 at the rear of the side wall portion 22, the blank being so cut and developed that when the end wall portions 26 and 27 are folded into proper position they will be disposed at an inclination or 60 in upwardly converging relation. The reinforcing portions 30 and 31, as well as portions 32 and 33, are bent laterally from the supporting portion 24 with the portions 32 and 33 suitably curved, and, if necessary, 65 spun into shape, so that the upper ends

of the reinforcing portions 32 and 33 will bear upwardly and against the bottom wall 23 so as to give rigidity to the oiler as a whole, as will appear more fully hereinafter. The supporting portions 24 and 25 are provided with registering openings or apertures 36 adapted to receive or fit over the threaded end 14 of the shaft 12, as is clearly shown in Fig. 2.

It will be apparent, from the above, that 75 the oiler comprises a container having upwardly inclined end walls with depending drip projections 28 and 29 at both ends of the container, the container also having a reinforced depending supporting portion 80 comprising the member 24 and 25 by which the oiler may be secured in position upon the trip lever. The depending supporting portion is preferably located between the end of the tapered portion 11 of the shaft 85 12 and the washer 15, the nut 13 constituting common means for securing the oiler in place upon the shaft 12 as well as for securing the trip lever upon the shaft 12. The trip lever is conveniently provided with a squared portion 37 against the lateral faces 90 of which contact or engage the laterally extending reinforcing portions 30 and 31, which engagement prevents relative angular movement between the supporting portion of the oiler and the trip lever, thereby maintaining the oiler and trip lever fixed with the container in elevated position above the trip lever so that the depending dripping portions will be located above the rollers 6 and pins 7 for a purpose more fully 100 hereinafter disclosed. The reinforcing portions 32 and 33 are upwardly curved as well as extending laterally from the supporting portion of the oiler with the upper 105 end of the curved portions bearing against and supporting the bottom 23 of the container so as to give rigidity to the container and to prevent the same from sagging during its operation.

Within the container is placed a suitable oil retaining means 38 of absorbent material such as felt or wick-like substance adapted to retain, by capillary attraction, a suitable quantity of oil but to also permit a slow 115 flow of the oil therefrom as the oiler is oscillated or given a snap action by the oscillation of the trip lever. The oil retaining means will also act as a filtering means thereby removing foreign substances from the 120 oil before the oil is conveyed to the parts to be lubricated. The bottom portion 23 of the container is preferably formed with the ends thereof slightly spaced from the inner faces of the end wall portions or depending drip 125 portions 28 and 29, the spaces thus formed between the ends of the bottom and the drip portions forming openings 39 in the shape of slots through which oil may be conducted from the oil retaining means in the con- 130

tainer to the drip portions, the oil adhering to and flowing along the surface of the drip portions and forming globules or drops near the lower end thereof, which, upon the oscillation of the oiler or the trip lever, may be cast from or caused to drop from the drip portions to the parts of the oscillating mechanism to be lubricated. The oil retaining means is pressed into position and 10 slightly compressed at the ends by the upwardly converging end wall portions 26 and 27, the inclination of the latter being of utility to prevent the working of the oil retaining means out of the container and from 15 being loosened or thrown from the container during action of the tripping mechanism.

It will be observed that the container is located above the yoke 8 and the trip lever in such position that the lowermost point of 20 the dripping portions 28 and 29 will lie substantially in the vertical plane passing between the inner surface of the rollers 6 and the adjacent surface of the yoke 8 so that the oil will fall or drop onto these members and will work its way between these surfaces as well as upon the bearing surface of the pins 7 and rollers 6 to lubricate the same. Oil will continue to flow along the trip lever to the lower end thereof and along 25 the surface 19 lubricating the same for contact with the roller 16 carried by the engine flywheel. In this way lubrication of several points by a single unitary device is continuously obtained during the operation of the 30 oscillating mechanism.

It will also be observed that the oil container has a permanently opened top and is elongated so that the oil may be poured into the container upon the oil retaining means 40 at any time, especially when the oscillating mechanism is in operation. The oil will seep through the oil retaining means and gradually flow through the openings or slots 39 onto the drip projections from which the 45 drops of oil may be snapped or thrown upon the parts to be lubricated during the oscillation of the trip lever and the oiler.

In operation the roller 16, carried by a moving part of the engine, such as a flywheel, contacts with the surface 19 of the trip lever, causing said lever to be shifted from the position shown in full lines to that shown in dotted lines, in Fig. 1 of the drawing, during which time the shaft 12, carrying the oscillating armature of the magneto, is given a certain angularly movement, and the springs 15 are tensioned by reason of the rollers 6 and pins 7 being angularly moved about the axis of the shaft 12 to a 55 point where the roller 16 disengages with the end of the trip lever, whereupon the springs 5, due to their contractile effect, suddenly oscillate the trip lever in reversed direction, the oiler being also oscillated simultaneously, since it is rigidly secured in

fixed relation to the trip lever. This snap action, due to the oscillation of the trip lever and oiler, will aid the oil to flow from the container onto the drip projections and will also cause the drops of oil adhering to the 70 drip projections to be cast therefrom and upon the parts to be lubricated, such as the surfaces between the rollers 16, yoke 8 and pins 7, the oil eventually flowing down along the trip lever to the surface 19, thus lubricating said surface for contact therewith of the roller 16. When the operation of the device ceases there is no tendency for the oil to be thrown from the container and the oil retaining means will retain the oil, by capillarity, with a minimum loss. 75

Having thus described my invention what I claim is:

1. In an oscillating device having an oscillatory mechanism including a shaft and a trip lever secured to said shaft, an oiler carried by said trip lever to oscillate therewith.

2. In an oscillating device having an oscillatory mechanism including a shaft and a trip lever secured to said shaft, the combination of an oiler carried by said trip lever to oscillate therewith and comprising means on said oiler engaging said trip lever for maintaining said oiler and lever in fixed relation. 90

3. In an oscillating device having an oscillatory mechanism including a shaft and a trip lever secured to said shaft, the combination of an oiler carried by said trip lever to oscillate therewith and comprising laterally extending portions engaging said trip lever for maintaining said oiler and lever in fixed relation. 95

4. In an oscillating device having an oscillatory mechanism including a shaft, and a trip lever secured to said shaft and having a squared portion, the combination of an oiler carried by said trip lever to oscillate therewith, and means on said oiler engaging said squared portion of said lever for maintaining said oiler and lever in fixed relation. 100

5. In an oscillating device having an oscillatory mechanism including a shaft and a trip lever secured to said shaft, an oiler carried by said trip lever to oscillate therewith, and common means for rigidly securing said lever to said shaft and said oiler to said lever. 115

6. In an oscillating device having an oscillatory mechanism including a shaft and a trip lever secured to said shaft, the combination of an oiler carried by said trip lever to oscillate therewith and comprising means engaging said trip lever for maintaining said oiler and lever in fixed relation, and common means for rigidly securing said lever to said shaft and said oiler to said lever. 120

7. In an oscillating device having an oscillatory mechanism including a shaft and a 130

4
trip lever secured thereto, the combination of an oiler comprising a container having a supporting portion by which said container may be carried on said trip lever and means for rigidly securing said supporting means to said trip lever.

8. In an oscillating device having an oscillatory mechanism including a shaft and a trip lever secured thereto, the combination 10 of an oiler carried by said trip lever to oscillate therewith and comprising a container having a supporting portion, and means for securing said supporting portion to said trip lever, said supporting portion being provided with means for maintaining said oiler in fixed relation to said lever.

9. In an oscillating device having an oscillatory mechanism including a shaft and a trip lever secured thereto, the combination 20 of an oiler carried by said trip lever to oscillate therewith and comprising a container having a supporting portion, and means for securing said supporting portion to said trip lever, said supporting portion being provided with means for maintaining said oiler in fixed relation to said lever and means bearing against and supporting the bottom of said container.

10. In an oscillating device having an oscillatory mechanism including a shaft and a trip lever secured to said shaft, the combination of an oiler carried by said trip lever to oscillate therewith and having a permanently open top.

35 11. In an oscillating device having an oscillatory mechanism including a shaft and a trip lever secured to said shaft, the combination of an oiler carried by said trip lever to oscillate therewith and comprising 40 an oil container having a permanently open top, and means for retaining oil in said container.

12. In an oscillating device having an oscillatory mechanism including a shaft and a trip lever secured to said shaft, the combination of an oiler carried by said trip lever to oscillate therewith and comprising an oil container having a permanently open top, means for retaining oil in said container, and means for retaining said oil retaining means in position during the oscillating of said lever and oiler.

13. In an oscillating magneto having a tripping mechanism including a shaft and a trip lever secured to said shaft, the combination of an oiler carried by said trip lever to oscillate therewith and comprising an oil container having a permanently open top, and means for retaining the oil in said container, said container having upwardly converging end walls for retaining said oil retaining means in position within said container during the oscillation of said lever and oiler.

65 14. In an oscillating device having an os-

cillatory mechanism including a shaft, a trip lever keyed to said shaft, rollers on said lever, springs connected to said rollers and to a fixed part of said device for normally urging movement of said trip lever in one direction and means for moving said lever in the opposite direction, the combination therewith of an oiler carried by said trip lever to oscillate therewith and comprising an oil container having a permanently open top, and means for retaining oil in said container, said container being provided with means for dripping oil between said rollers and said lever for lubricating the same.

15. In an oscillating device having an oscillatory mechanism including a shaft and a trip lever secured to said shaft, the combination of an oil container carried by said trip lever to oscillate therewith, comprising means for retaining the oil in said container, means for retaining said oil retaining means in position within said container during the oscillation of said lever and oiler, and oil dripping means connected to said container for directing drops of oil to the parts to be lubricated on said oscillatory mechanism.

16. In an oscillating device having an oscillatory mechanism including a shaft and a trip lever secured to said shaft, the combination of an oiler carried by said trip lever to oscillate therewith, and comprising an oil container having a permanently open top, and means for retaining oil in said container, said container being provided with depending drip projections for dripping oil upon 100 said lever during the oscillation thereof.

17. In an oscillating device having an oscillatory mechanism including a shaft and a trip lever secured to said shaft, the combination of an oil container carried by said trip 105 lever to oscillate therewith and comprising means for retaining the oil in said container, said container having openings through which the oil may flow from the oil retaining means to the exterior of the container during 110 the oscillation of said lever and oiler.

18. In an oscillating device having an oscillatory mechanism including a shaft and a trip lever secured to said shaft, the combination of an oil container carried by said trip lever to oscillate therewith and comprising means for retaining the oil in said container and means for retaining said oil retaining means in position during the oscillation of said lever and oiler, said container being provided with depending oil drip projections located to drip upon parts to be lubricated on said tripping mechanism and having slots at the bottom of said container adjacent said projections for feeding 125 oil thereto.

19. An oiler adapted for use with an oscillating device having an oscillatory mechanism, composed from a single sheet metal blank having container sides, bottom and 130

- end wall portions, and a supporting portion by which the container may be rigidly secured to said oscillatory mechanism.
20. In an oiler adapted for use in an oscillating device having an oscillatory mechanism including a shaft and a trip lever, composed from a single sheet metal blank having side and end portions and a supporting portion, the latter being provided with reinforcing portions adapted to be laterally bent to engage with said trip lever to maintain said oiler and trip lever in fixed relation.
21. An oiler adapted for use with an oscillating device having an oscillatory mechanism, composed from a single sheet metal blank having container side, bottom and end wall portions, and a supporting portion by which the container may be rigidly secured to said oscillatory mechanism, said supporting portions having reinforcing portions for giving rigidity to said oiler, and drip portions integral with said end wall portions.

In testimony whereof I affix my signature.

ADOLPH ROSNER.
